UNITED STATES PATENT OFFICE

CLARENCE B. YOUNT, OF NEAR DAYTON, OHIO, ASSIGNOR TO TRUPAR MANUFACTURING COMPANY, OF DAYTON, OHIO, A CORPORATION OF OHIO

DEEP WELL PUMP

Application filed July 12, 1929. Serial No. 377,643.

This invention relates to new and useful improvements in deep well pumps.

It is one of the principal objects of my invention to provide a compact and efficient deep well pump for domestic use.

It is another object of my invention to provide a simple, automatic and efficient oiling system for my deep well pump.

Other important and incidental objects will be brought out in the following specification and particularly set forth in the subjoined claims.

In the accompanying drawings illustrating my invention, Figure 1 is a side elevational view of my deep well pump, partly in section. Figure 2 is a front elevational view of the same, with the front cover removed. Figure 3 is an enlarged top plan view of the cross-head guide rod guides, the wrist pin and the oiling means for the same. And Figure 4 is a perspective view of the arched deflecting member and the slotted tubes to which it is attached.

Referring to the accompanying drawings for a detailed description of my invention, the numeral 1 designates the base portion of a pump casting having two vertical walls 2 and 3 formed with oppositely disposed holes to receive bearings 4 and 5 for a main gear shaft 6.

Secured to the inner end of the shaft 6 is a gear 7 which meshes with a pinion 8 fast on a shaft 9 journaled in bearings 10 and 11 mounted in holes in the upper portions of the casting walls 2 and 3 respectively. Fast on the outer end of the shaft 9 is a large pulley 12 which receives a belt 13 that passes around a small pulley 14 secured to the armature shaft 15 of a heavy duty motor 16. The latter is mounted on a bracket 17 secured to the wall 3 of the pump casting.

Secured to the gear 7 is a crank pin 18 to which the lower end of a connecting rod 19 is fitted by a roller bearing connection 20.

By means of a wrist pin 21 the connecting rod 19 is secured at its upper end to the upper end of a cross head 22. The latter comprises a casting formed with two spaced cylindrical guides 23, 23 connected by a web 24 having a rearwardly projecting top portion 25.

Formed on the rear end of the latter is a downwardly projecting flange 26 containing a hole that receives the outer end of the wrist pin 21, the inner end of which is received by a hole in the upper portion of the web 24. (See Figures 1 and 3).

Between the outer ends of two flanges 27, 27 on the top projecting portion 25 of the web 24, there is formed in said projecting portion an oval hole 28 through which oil is discharged upon the wrist pin 21 from means to be hereinafter described.

The cross head guides 23, 23 are free to slide up and down over guide rods 29, 29, respectively, secured between the top and bottom portions of the casing. When reciprocated by the connecting rod 19, the cross head, so guided, will actuate the upper section 30 of the pump rod. The latter has a reduced upper end which projects through a hole in an arm 31 that extends outwardly from the upper portion of the cross head. At its lower end the rod 30 terminates in a reduced threaded part 32 equipped with a piston or plunger 33 which is free to slide in a pump cylinder 34. By means of a differential head pump rod coupling 35, the rod 30 is adapted to be connected to a drop pipe pump rod 36.

Secured to the upper reduced end of the pump rod 30, by means of a nut 37, is a U piece 38 that is set on its side so that its top arm, which is longer than its other arm, will project over the rod. Connected to the free end of the U piece 38 is the upper end of a rod 39 to whose lower end there is attached the plunger or piston 40 of an air pump cylinder 41. The latter is secured to a fitting 42 which is screwed into the water discharge portion 43 of the casting 44 which receives the upper end of the pump cylinder 34. Also communicating with the discharge line 45 is a customary air chamber 46. Supported upon the latter is an automatic switch 47 for controlling the operation of the motor 16 to which it is connected by a cable 48.

For the purpose of automatically oiling the guides 23 and wrist pin 21, I provide the following means. Secured to the shaft 9 between the pinion 8 and the bearing 11, is a metal disc 49. When the pump is in opera-

tion, the gear 7, which turns in oil below its axis, will carry this oil up to the pinion 8. The rotating engagement of this pinion with the gear will splash this oil upon the disc 49. The latter, being also in rotation, will then whirl it to the top of the casing, where the following means direct it to the guides and wrist pin.

Projecting rearwardly from each guide 23, 10 and communicating therewith, is a tube 50. Formed in the top portion of each tube at its rear end is a slot 51. Projecting up from the rear end of one tube 50 and over and down to the rear end of the other tube, is a flat 15 arched deflecting member 52. One end of this member uncovers the slot 51 in one tube, while the other end of the deflecting member covers the slot 51 in the other tube. Since the arched deflecting member is above the disc 49, part of the oil whirled upwardly by the latter will strike the under surface of said deflecting member. Part of this oil will be directed downwardly by this deflecting member to the slot 51 in the tube 50 over 20 which it extends. Through this slot the deflected oil will pass into the tube, through which it flows into its respective guide 23 to thoroughly lubricate it. Part of the oil thrown to the top of the casing by the disc 25 49 will drop through the uncovered slot 51 in the other tube 50, by which it is carried to its respective guide 23 to thoroughly lubricate it. Thus it is seen that both guides are automatically lubricated by the disc and associated means to permit them to slide freely 30 upon the cross head guide rods 29.

Part of the oil which strikes the under-surface of the deflecting member 52, is directed by a tapered and downwardly inclined 40 trough 53 to the oval hole 28 in the rearwardly projecting portion 25 of the web 24. Through this hole the deflected oil descends to the wrist pin 21 to automatically and thoroughly lubricate it. The upper end of the 45 inclined trough is secured to the rear edge portion of the arched deflecting member 52 so that a maximum amount of oil will drop into it from the top of said member.

It is thus seen that the wrist pin 21 as 50 well as the guides 23, will be automatically and thoroughly lubricated by the disc 49, arched member 52, the tubes 50, 50 and the inclined trough 53 during the operation of the pump. Oil whirled to the top of the 55 casing by the disc 49 will also lubricate other moving parts in the path of its descent.

Having described my invention, I claim:

1. In a deep well pump, the combination 60 with a casing adapted to contain a lubricant, a pair of vertical guide rods, a cross head having sleeves reciprocable on said guide rods, operating means for said cross head extending into the oil in the casing, a deflecting member carried by said sleeves, and means for 65 whirling the lubricant from the bottom of the

casing into contact with the deflecting member, for the purpose specified.

2. In a deep well pump, the combination 70 with a casing adapted to contain a lubricant, a pair of vertical guide rods, a cross head having sleeves reciprocable on said guide rods, operating means for said cross head extending into the oil in the casing, an arched deflecting member carried by said sleeves, means for whirling the lubricant from the 75 bottom of the casing into contact with the deflecting member, and means for conducting the lubricant from the deflecting member to the sleeves of the cross head for the purpose specified. 80

3. In a deep well pump, the combination 85 with a casing adapted to contain a lubricant, a pair of vertical guide rods, a cross head formed with sleeves reciprocable on said guide rods, operating means for said cross head extending into the lubricant in the casing, a lubricant conveying element communicating with, and projecting from, each sleeve, a device connected to the operating means for whirling the lubricant to the top of the 90 casing, and an arched deflecting member in the path of said lubricant, and connected at each end to a respective lubricant conveying element for the purpose specified. 95

4. In a deep well pump, the combination 100 with a casing adapted to contain oil, a pair of vertical guide rods, a cross head formed with sleeves reciprocable on said guide rods, operating means for said cross head extending into the oil in the casing, an oil-conveying tube, having a slot in the top portion of its outer end and communicating at its inner end with each sleeve, by which it is supported, a device connected to the operating means for whirling oil to the top of the casing, and an arched deflecting strip in the path of said oil and connected at each end to a respective oil conveying tube, for the purpose specified. 105

5. In a deep well pump, the combination 110 with a casing adapted to contain oil, a pair of vertical guide rods, a cross head formed with sleeves reciprocable on said guide rods, operating means projecting into the oil, a connecting rod between said operating means and the cross head, a member connected to the operating means for whirling the oil to the top of the casing, an arched strip carried by the cross head in the path of the upwardly projected oil, and a trough inclining downwardly from the deflecting strip to discharge 115 oil onto the connection between the cross head and connecting rod.

6. In a deep well pump, the combination 120 with a casing adapted to contain oil, a pair of vertical guide rods, a cross head formed with sleeves reciprocable on said guide rods, operating means projecting into said oil, a connecting rod secured at its lower end to the operating means, a wrist pin carried by the cross head, the upper end of the connecting 125 rod, 130

rod being secured to the wrist pin, a disc connected to the operating means for whirling the oil to the top of the casing, a flat projecting portion of the cross head formed with a hole over the wrist pin, an arched deflecting strip carried by the cross head in the path of the upwardly projected oil, and a trough member inclining downwardly from the undersurface of the deflecting strip to a point above said hole, to discharge oil therethrough upon the wrist pin.

In testimony whereof I have hereunto set my hand this 10th day of July, 1929.

CLARENCE B. YOUNT.
